UNITED STATES PATENT OFFICE.

FERNAND BOYER, OF PARIS, FRANCE.

APPARATUS FOR PREVENTING THE LATERAL CONTRACTION OF A FABRIC DURING THE PROCESS OF WEAVING.

Application filed November 26, 1920. Serial No. 426,433.

To all whom it may concern:

Be it known that I, FERNAND BOYER, manufacturer, a citizen of France, residing at Paris, in the Republic of France, have invented certain new and useful Improvements in Apparatus for Preventing the Lateral Contraction of a Fabric During the Process of Weaving, of which the following is a specification.

10 Weaving machines as constructed at the present time operate in such a manner that the finished fabric becomes contracted, that is to say narrower than the distance between the extreme warp threads when the 15 warps are spread out as they are immediately before the completion of the fabric. The result of this is that the present day weaving machines are not suitable for the manufacture of all kinds of fabrics, making 20 it necessary for fabrics which must be unconditionally of the same width as the warp to be produced by hand. The present invention relates to a method for preventing the lateral contraction of a fabric during the 25 process of weaving and consists in laying the weft thread in a serpentine line on the ground of the shed in such a way that on applying pressure to the finished fabric no 30 contractive action takes place either in the case of the weft thread nor that of the warp threads.

The invention also relates to an apparatus for carrying out this method, the distinguishing feature of which is that the 35 shuttle which inserts the weft thread in the shed is provided with rotating devices which bring the weft thread as it runs from the shuttle gradually from one side in a wavy form and secondly with guides which bring 40 the thread as it runs from the shuttle spool into the path of these devices.

In the drawing:

Fig. 1 is a side elevation of the weaving machine illustrating my present invention.

45 Fig. 2 is a side elevation of the same.

Fig. 3 is an elevation and partial cross section showing the relationship of the bars and shafts employed to operate the shuttle and mechanism associated therewith.

50 Fig. 4 is a cross section on line *h*—*h*, Fig. 1.

Fig. 5 is an enlarged elevation of the shuttle and the devices associated therewith.

Fig. 6 is an end elevation and partial

cross section illustrating these shuttle devices.

Fig. 7 is an end elevation of the same parts including the guides for directing the thread as the same comes from the shuttle.

Fig. 8 is an enlarged section on line *g*—*g*, Fig. 4.

Fig. 9 is a sectional elevation showing the vertical dimensions of the guide rollers and the parts associated therewith.

Fig. 10 is a side elevation of the frame of the apparatus.

Fig. 11 is a view similar to Fig. 1 showing a modified form of the invention, and

Fig. 12 is an end elevation of the same.

The constructional form shown in Figs. 70 1 to 7 shows an apparatus for preventing a fabric from becoming narrower during the process of weaving. 8 (see Figs. 1 and 2,) is a machine frame, which carries on one side the bracket 9. To the machine frame 8 75 is also rigidly connected the carrier 10. To the bracket 9 and the carrier 10 is screwed the front shuttle guide 11. On the carrier 10 is also mounted the slay guide 13 in the channel of which slides the roller which is 80 carried on the bolt 15. This bolt 15 is carried on the beater arm 16 which carries the slay 2 at the bottom between the holders 17 and 18, (see Fig. 7).

The rigid connection of the carrier 10 85 with the frame is obtained not only by being screwed to the transverse cross beam 91 (Fig. 9) which connects the top of two machine frames but also by the shuttle guides 11 and 12 (Figs. 1 and 6) which are screwed onto 90 the carrier 10 and bracket 9; the latter being fixed to the frame 8 a rigid connection is also obtained for the lower part.

The slay 2 may give a blow in vertical direction since its carrier 16 is linked to 95 the blow lever 93 by the shaft 92. The shaft 94 imparts to the blow lever its rotating movement for carrying out the blow in the direction of the arrow *i* (Fig. 9). If the carrier 16 and with it the slay 2 is swung 100 downwardly, the roller 14 slides in the channel of the slay guide 13 downwardly and the bolt 15 constitutes in each position the pivot for equalizing the radial movement of the lever 93. Fig. 10 shows how the 105 bracket 9 is screwed onto the frame 8, the bearings of the hollow shaft 32 being marked 32', while the bearings of the shaft

36 are indicated at 36' and the bearing of the thrust bar 48 at 48'.

Under the slay and through the opened shed between the warp threads 1 and over 5 the finished point 4 is driven the shuttle 19 which is carried underneath the bearings 20 and 21. On the left hand side of the shuttle is a screw 22 and on the right hand side a screw 23, both of which screws are connected 10 with a shaft working in the bearings 20 and 21. The shuttle 19 carries the removable shuttle box 24, (see Fig. 5) in which the shuttle spool is placed. From this shuttle spool 25 the weft thread runs through the 15 slot 26 in the box into and through the guides 27 and 28 into the middle of the shed and thence according to requirements under the screws 22 or 23 (see Figs. 1, 5 and 7). In front of the screws 22 and 23 are the 20 screw points 29 and 30 (see Figs. 1, 5 and 7) which are provided with a longitudinal groove 31, (see Fig. 7). In the bracket 9 rotates the hollow shaft 32, which carries the gear wheel 33 (see Figs. 1, 3 and 4). The 25 gear wheel 33 is prevented from falling out of the bracket 9 by the locking ring 34 mounted on the hollow shaft 32, (see Fig. 4.) The gear wheel 33 is driven by the gear wheel 35 which is rigidly connected to the 30 gear wheel 37 by a shaft 36 rotating in the bracket 9. The hollow shaft 32 guides the rotating rod 38 which can slide forwards or backwards and is provided with a longitudinal groove 39. In the hollow shaft 32 is 35 placed the key 40 which engages in the longitudinal groove 39. In consequence of this arrangement the rotating rod 38 when it slides forwards or backwards also takes part on the rotation of the gear wheel 33. The 40 rotating rod 38 has in front a hollow space 41 (see Figs. 4 and 5) in which the point of the screw 29 or 30 can enter. In line with this hollow space 41, in a slot in the rotating rod 38, is arranged the tappet trap 42, which 45 can be turned up in the manner shown in Fig. 4 in the direction of the arrow, but is always held in the shut position by the pressure of the spring 43 on the ball 44. If the shuttle 19 or the point of a screw 29 or 30 50 be inserted in the hollow space 41, the trap rises in the direction of the arrow in Fig. 4. As soon as the rotating rod 38 rotates with the wheel 33 and offers the slightest resistance to a screw 22 or 23 the trap 42 is 55 brought over the groove 31, snaps into this under the pressure of the spring, thus establishing a rigid connection and the screws 22 and 23 are compelled to take part in the rotations of the rod 38, (see Fig. 5). Conversely 60 this coupling is released as soon as the shuttle 19 becomes stationary and the rotating rod 38 is drawn back.

On the bracket 9 are also mounted the two guides 45 and 46, (see Figs. 1 and 3) which 65 are both provided with a top slot 47. In

these two guides 45 and 46 slides forwards or backwards the thrust bar 48, which is guided in the corresponding part of the shuttle 19. In the shuttle 19 is a wedge-shaped groove 49, (see Figs. 6 and 7) on the 70 thrust bar 48 is carried a corresponding wedge. When the thrust bar 48 is inserted in the shuttle 19 no rotation of the shuttle can take place no matter in what position it may be. The thrust bar 48 is connected to 75 the rotating rod 38 by the hanger 50. While on the one hand the hanger 50 is screwed fast to the thrust bar 48 it forms on the other hand the bearing in which the rod 38 rotates (see Figs. 1 and 2.) To the left and right 80 of this bearing the locking rings 51 and 52 are rigidly connected to the rotating bar 38 so that this latter is compelled to take part in the forward or backward movement of the thrust bar 48 no matter whether the bar 85 38 be rotating or not. On the frame 8 of the machine is also mounted the bracket 53. At the back of the bracket 53 on a shaft 54 is mounted the rotating worm wheel 57. The shaft 54 rotates in the bearings 55 and 56 (see Figs. 1 and 2), and on the same shaft and rigidly connected to the worm wheel 57 is mounted the chain wheel 58. On a shaft 59 which is screwed to the shuttle guide 11 is mounted a two part chain wheel 95 60 (see Fig. 1). Over these chain wheels 58 and 60 is passed the chain 61, the ends of which are secured in a block 62, which latter is rigidly connected to the thrust bar 48. By rotating the worm wheel 57 in one direction or the other, the chain 61 is set in motion, and thereby the thrust bar 48, is pushed forwards or backwards and with it the rotating rod 38 also is moved.

On the frame 8 of the machine (see Figs. 1 and 2) is also mounted the bearing 63. The bracket 53 carries the bearing 64 and in these bearings 63 and 64 is journaled the shaft 65 which carries on one end of it the worm 66 which gears into the worm wheel 57. On the 105 other side and rigidly mounted on the shaft 65 is the bevel wheel 67 which gears in to the bevel wheel 68. This bevel wheel 68 is fixed on the vertical driving shaft 69 which is adapted to rotate in the bearings 70, 71 110 and 72. On the shaft 69 is also rigidly mounted the bevel wheel 73 which gears with the bevel wheel 37.

On the shuttle 19 between and above the bearings 20 and 21 are mounted the thread 120 guides or guide bars 74 and 75, (see Figs. 5 and 7), which, when the shuttle is driven through the shed conduct the warp threads out of the screw 22 into the screw 23 or vice versa. Fig. 5 shows the shuttle 19 in the 125 position of rest, that is to say, the shuttle is, in contradistinction to the position shown in Fig. 1, moved to the left out of the fabric, so that the blow of the slay 2 can take place unimpeded. In this position the shuttle 19 130

is supported by its upper part in the slots 76 and 77 in the guides 11 and 12, (see Fig. 6).

The action of the apparatus is as follows:

The shuttle 19 is driven out of the position of rest (see Fig. 5) in the direction of the arrow *e* in Fig. 1 through the fabric. For this purpose the driving shaft 69 is correspondingly rotated. The bevel wheel 68 connected to this shaft transmits the rotation 10 to the bevel wheel 67 and consequently to the worm 66. This latter rotates the worm wheel 57 and consequently the chain wheel 58 turns. The chain wheel 58 drives the chain 61 and this latter carries forward the block 62 together with the thrust bar 48. The thrust bar 48 carries with it the rotating rod 38 by the hanger 50. By the rotation of the shaft 69 the bevel wheel 73 likewise transmits rotation to the bevel 20 wheel 37 and consequently to the gear wheel 35 which transmits this rotation to the gear wheel 33 and to the hollow shaft 32. The rotating rod 38 is consequently set in rotation by the key 40 and this rotation is transmitted 25 by the tappet trap 42 to the screws 22 and 23. Owing to the fact that the bar 48 thrusts the rotating rod 38 forwards, while it rotates together with the screws, the screws 22 and 23 which engage with the warp 30 threads screw themselves through the shed, whereby the shuttle thread 7 which runs out is guided under the screw 22 which presses it down to the bottom of the shed at the finished point 4 whereby it is immediately 35 laid in a serpentine line (see Figs. 1 and 11). As the downward depression takes place successively from one side, the shuttle spool can have as much thread taken from it as is necessary for the serpentine 40 insertion, that is to say, more if necessary than the width of the fabric. The operation can be clearly seen from Fig. 1 in which for the sake of clearness the warp threads lying in front of the 45 shuttle are omitted. The advance of the bar 48 is naturally so regulated that it corresponds to the pitch of the screws 22 and 23. The pitch of these screws also depends on the distance between the warp threads 1. 50 The same arrangement is provided on the side of the machine opposite that shown in Fig. 1 in order to enable the shuttle to be driven through in the opposite direction to that of the arrow *e* after the blow and the 55 change of the threads. If, therefore, the shuttle 19 has passed completely through the fabric, when the block 62 on the rod 48 can pass through the slot 47 in the guides 45 and 46, the shuttle 19 will be impelled 60 directly against the rod 48 and the rotating bar 38 in the side of the machine opposite that shown in Fig. 1. By means of devices which are not shown in the drawing the shuttle is held fast, the driving shaft 69 rotates in the reverse direction and guides the 65 rods 48 and 38 back into their position of rest, the tappet trap 42 at once disconnecting itself as above described from the point of the screw 29 or 30. When both rods are in the position of rest, the slay 2 delivers its 70 blow and at the same time the change of the shed takes place. The operation is repeated, that is to say, the shuttle 19 is driven through the shed by similar devices from the opposite side of the machine in the direction 75 of the arrow *e* in Fig. 1. It should also be stated that when the shuttle is driven through the shed, the screw 22 or 23 which is moving in front runs idly and only the rear one effects the pressing in of the thread. 80 The double arrangement of the screws however, enables the operation to be carried out from both sides, as is necessary in weaving machines. The warp threads 1 are brought on to the guide bars 74 and 75 85 (see Fig. 1) on which they slide unimpeded when the shuttle is driven through the shed.

Another form of the invention is shown in Fig. 11 and 12 of the accompanying drawing. For the sake of clearness the warp 90 threads lying in front of the shuttle 19 have also been omitted. On the shuttle itself the screws 22 and 23 are dispensed with and in their place are mounted the gear wheels 78 and 79 (see Fig. 11.) These gear 95 wheels 78 and 79 lie in a slot in the extensions 80 and 81 of the shuttle and rotate on the shafts 82 and 83. In front of the warp threads 1 is rigidly mounted the rocking lever 84 on a shaft 85 which latter rotates 100 in a bearing 86 (see Figs. 7 and 11). This arrangement is of course provided on both sides, that is to say, on the left and right of the fabric. On the top of the rocking lever is mounted the rule 87 which runs from end 105 to end and which is provided with a weft thread carrier 88 which terminates in a point. This weft thread carrier 88 corresponds to the distance apart of the warp threads 1 and forms a rack under the gear 110 wheels 78 and 79. The pitch of the gear wheels 78 and 79 naturally corresponds to the pitch of this rack. The rocking lever 84 can be swung back in the direction of the arrow in Fig. 12 and right down into the 115 position shown in the drawing. The bracket 9 (see Fig. 11) only carries the guides 45 and 46, as the rotating rod 38 with all the devices connected therewith is dispensed with. To drive the shuttle through the 120 shed only the thrust bar 48 is necessary, which bar is driven backwards and forwards by similar devices to those described and shown in Fig. 1. The extensions 80 and 81 of the shuttle are connected by the 125 struts or ladders 89 and 90, over which the warp threads slide as they do over the guide bars 74 and 75 (see Fig. 1).

The action of this apparatus is as follows:

The rocking lever 84 is swung into the 130

position shown in Fig. 12, the weft thread carriers 88 passing above the finished point 4 through the warp threads 1. The shed is opened and the shuttle 19 is driven into the 5 shed and through it in the direction of the arrow *f* in Fig. 11 in the manner which has been already described. The gear wheels 78 and 79 move into the path of the weft thread carrier 88 which forms a rack and 10 are thereby caused to rotate. The weft thread 7 unwinds itself as previously described from the shuttle spool 25 and passes in through the guides 27 and 28 into the middle of the shed.

15 While the gear wheel 79 runs idly through the shed the weft thread 7 is brought under the rear gear wheel 78 and is pressed in a serpentine line between the wheel and the rack. When the shuttle 19 20 has been driven sufficiently far forward, it is taken up by a thrust bar on the side opposite to Fig. 11 and held fast by devices not shown here. The thrust bar 48 shown in Fig. 11 returns to its original position and during this time the lever 84 swings in the direction of the arrow in Fig. 12 downwards, the weft thread being stripped off the rear warp threads 1 and remaining in the middle of the shed. The thrust bar 48 has in the meantime 25 passed to the rear and the slay 2 can make its blow, the lever 84 having been removed out of its path by the downward swing. By the blow of the slay 2 the weft thread 7 pressed into the serpentine line is rotated and laid at the finished point 4 is a horizontal serpentine line and correctly around the warp threads 1 the effect of which is that no tractive action takes place and any narrowing of the fabric is prevented. The slay 30 35 40 swings back, the shed is changed, the lever 84 swings upwards and the operation is repeated in the opposite direction to that indicated by the arrow *f* in Fig. 11, and so on. Whereas in ordinary fabrics the narrowing 45 action is of lesser importance, it is necessary in fabrics such as pile carpets for example, that the fabric and the warps remain of equal width, and consequently also that the stretched warp threads 1 remain in a straight 50 line, as ordinarily in such machines tools pass over the finished point 4 between the warp threads; which have to effect the formation of the knots.

I claim as my invention:

- 55 1. In an apparatus of the class described, a shuttle for inserting a weft into the shed, and rotary devices coacting with the shuttle for laying the weft in a serpentine path at the bottom of the shed.
- 60 2. In an apparatus of the class described, a shuttle for inserting a weft into the shed, rotary devices coacting with the shuttle for

laying the weft in a serpentine path at the bottom of the shed, and guides for directing the weft to the said rotary device.

65 3. In an apparatus of the class described, a shuttle for inserting weft threads into the shed, a thrust bar for moving the shuttle, rotary devices for laying the weft in a serpentine path at the bottom of the shed, and a guide for each rotary device for directing the weft into the same.

70 4. In an apparatus of the class described, a shuttle for inserting weft threads into the shed, a thrust bar for moving the shuttle, rotary devices for laying the weft in a serpentine path at the bottom of the shed, a rotary shaft for turning the said rotary devices, and a guide for each rotary device for directing the weft thereto.

75 5. In an apparatus of the class described, a shuttle for inserting weft threads into the shed, a shaft carried by the said shuttle, rotary devices mounted on the said shaft and adapted to lay the weft in a serpentine path at the bottom of the shed, a thrust bar for moving the shuttle, a rotary shaft for turning the said shaft carried by the shuttle and the rotary devices mounted thereon, means for moving the said rotary shaft longitudinally with the said thrust bar, and means for turning the said rotary shaft.

80 6. In an apparatus of the class described, a shuttle for inserting weft threads into the shed, a shaft carried by the said shuttle, rotary devices mounted on the said shaft and adapted to lay the weft in a serpentine path at the bottom of the shed, a thrust bar for moving the shuttle, a rotary shaft, means for connecting and disconnecting the said rotary shaft and the shaft carried by the shuttle, and guides for directing the weft into the path of the said rotary devices.

85 7. In an apparatus of the class described, a shuttle for inserting weft threads into the shed, a support for the said shuttle when the same is at rest, a thrust bar adapted to engage the end of the shuttle to shift the same, a shaft mounted and journaled in bearings carried by the said shuttle, rotary devices connected to the said shaft for laying the weft in a serpentine path at the bottom of the shed, a rotary shaft, means for connecting and disconnecting the rotary shaft to the shaft journaled in the bearings on the shuttle, means for moving the said thrust bar and rotary shaft together longitudinally, means for turning the said rotary shaft and guides for directing the weft into the path of the said rotary devices mounted on the shaft carried by the shuttle.

90 105 110 115 120 In testimony whereof I affix my signature.

FERNAND BOYER.
